UNITED STATES PATENT OFFICE.

ARTHUR L. BURTON, OF FAIRHAVEN, MASSACHUSETTS.

BOBBIN-CLEANING MACHINE.

1,321,884.

Specification of Letters Patent. Patented Nov. 18, 1919.

Application filed April 12, 1919. Serial No. 289,519.

To all whom it may concern:

Be it known that I, ARTHUR L. BURTON, a citizen of the United States, residing at Fairhaven, in the county of Bristol and State of Massachusetts, have invented certain new and useful Improvements in Bobbin-Cleaning Machines, of which the following is a specification, reference being had to the accompanying drawings.

10 This invention relates to devices for stripping or cleaning bobbins such as are used in the operations of spinning, doubling, twisting, roving, or other spooling operations, and the general object of the invention is to provide very simple and efficient means whereby the tail ends or unused portions of the yarns or "rovings" remaining on spent bobbins may be stripped from the bobbins at small cost, with rapidity, and without the necessity of using skilled labor.

15 A further object is to provide a construction of this character which requires very little power to run it, and which includes a rotatable stripping element having thereon 20 an outer sheet or covering formed of card clothing.

25 A further object is to provide a device of this character including a table, a rotatable stripping element, a guard housing normally 30 partially inclosing the stripping element but having an opening through which the stripping element slightly projects, and adjustable means for preventing the bobbin from being injured by the card clothing.

35 A further object is to provide for the ready removal or replacement of the rotatable element, and provide a compartment into which the strip waste from the combination is discharged.

40 Other objects will appear in the course of the following description.

My invention is illustrated in the accompanying drawings, wherein:

Figure 1 is a perspective view of a bobbin cleaning machine constructed in accordance with my invention;

Fig. 2 is a vertical sectional view through one of the housings and the cleaning roller showing the manner in which the machine 50 is used;

Fig. 3 is a sectional view through the housing and table showing the roller in elevation;

Fig. 4 is a fragmentary perspective view 55 showing the manner in which the housing turns back upon the table to expose the cleaning roller; and

Fig. 5 is a side view of a portion of the card clothing used on the roller.

Referring to the drawings, 10 designates a 60 table which may have any required length and which is supported at intervals by legs 11. This table is shown as supporting two bobbin cleaning devices. This, of course, is not an essential part of the invention. 65 Rotatably mounted above the table are one or more rotatable cleaning members 12, each having a shaft 13, the shaft being shown as provided with fast and loose pulleys engaged by a belt 14 which passes from a driving or countershaft, means being provided whereby the belt may be shifted from the loose to the fast pulley and vice versa.

70 The rotatable element is cylindrical in form and made of any suitable material, but 75 is covered upon its exterior face with a fillet of "card clothing" 15 having, as usual, very fine teeth projecting from its surface. Preferably, this strip of card clothing is taken 80 from cards which are too much worn to be 85 used for their original purpose, which card clothing would ordinarily be destroyed. I have found, however, that in actual practice 90 these pieces of worn card clothing may be used, and preferably will be used upon the 95 cleaning element. This fillet of card clothing is applied to the rotatable element in any desired way so that it may be removed and replaced with a new fillet whenever necessary.

99 Hingedly mounted upon the table 10 is a 100 housing 16 consisting of end members, and side members 17, the side members being preferably disposed in downwardly divergent relation, and one of these side members 105 being hinged to the table by the hinges 18. On each side member 17 there is provided a vertically movable slide 19 moving between guides 20 and having a vertically extending slot 21 through which passes a bolt 100 having a wing nut 22. The slide may thus be adjusted vertically and then clamped in its adjusted position. Both of these slides will be adjusted alike. A housing comprising a back board 23, a top board 24, and end 105 members 25 will extend over each cleaning device at a sufficient distance to give an operator plenty of room, and rearward of the cleaning roller this housing will be provided with a door 26 so as to form a partially open 110 compartment rearward of the cleaning device into which the fly waste will be discharged, as illustrated in Fig. 2.

Receptacles for holding the cleaned bob-

bins may be disposed beneath the table 10 so that the bobbins can be dropped therein by the operator as soon as cleaned.

In the operation of this device, the slides 5 19 are so set that the bobbin when disposed upon the upper edge of the slide will have the waste thereon engaged by the card clothing of the cleaning element, but preventing the bobbin itself being brought into contact 10 with the card clothing and thus injured. Trucks or receptacles containing bobbins to be cleaned are disposed near the left hand of the operator and the operator picks up a handful of the bobbins and with his right 15 hand passes one, two, or three bobbins at a time over the top of the guard box or housing 17, resting the bobbins upon the upper edges of the slides, and the rapidly rotating card clothing cleanses the bobbins. The 20 cleaned bobbins are then dropped into the receptacles below the table.

It will be seen that my machine requires no skilled labor in order to operate it, and that an entirely ignorant person can operate 25 the machine efficiently with no instructions at all. It has been found in practice that this device will clean nine thousand bobbins a day at each unit of cleaning cylinder, or eighteen thousand bobbins a day on the complete two-unit machine. This has been done 30 with unskilled labor working seven hours out of an eight-hour day.

The cleaning device will not damage bobbins and the "tail ends" or unused portions 35 of yarn or roving remaining on the spent bobbins, after being cleaned from the bobbins, is in as good or better condition for remixing with the regular yarn than the waste from any other bobbin cleaning machine known to me. There are no parts to 40 repair outside of renewing the card clothing on the rotatable cleaner and it does not require skilled labor in order to renew these cards.

45 It will be understood that after passing the bobbins over the rapidly revolving card clothing, the operator holds the bobbins over the waste cans which are disposed beneath the table 10 and merely slides the waste off 50 the bobbins with the tips of his fingers on the left hand. This roving waste is not thrown completely away by the card clothing and thrown into the compartment behind the door 26, and nothing but loose fly waste goes 55 into the space behind these doors 26, but the real roving waste is deposited in the cans or other receptacles disposed beneath the tables, the discharge of this roving waste being indicated in Fig. 2.

60 I am aware that automatic bobbin cleaning machines have been proposed, but all of these machines required skilled labor to operate and they are sufficiently delicate in

structure to readily get out of order and require expensive repairs to be made. I am 65 also aware that bobbins have been cleaned by means of card clothing, but in this case a strip of card clothing has been tacked to a piece of wood and the bobbin has been scraped by hand against the card clothing 70 to remove the waste. This is a long and tedious operation. In actual operation the cleaning roller 12 should be rotated at a speed of 1200 R. P. M. and $\frac{1}{2}$ of 1 H. P. is required for each unit of two cleaners. 75

While I have illustrated certain details of construction and arrangement of parts, which I have found to be thoroughly effective in actual practice, yet I do not wish to be limited to this, as it is obvious that many 80 changes might be made in the details of construction and arrangement of parts without departing from the spirit of the invention.

I claim:—

1. A bobbin cleaning machine including a 85 table, a rotating cleaning element mounted upon the table and having its periphery covered with card clothing, a housing partially inclosing the cleaning element and having side walls extending parallel thereto and 90 formed with vertical guides, oppositely disposed slides mounted on the side walls in said guides and vertically adjustable with relation to the side walls and the cleaning element and against the upper ends of which a 95 bobbin is adapted to be disposed for cleaning.

2. A bobbin cleaning machine including a 100 table, a rotating cleaning element mounted upon the table and having its periphery covered with card clothing, a housing partially inclosing the cleaning element and having side walls extending parallel thereto and 105 formed with vertical guides, oppositely disposed slides mounted on the side walls in said guides and vertically adjustable with relation to the side walls and the cleaning element and against the upper ends of which a bobbin is adapted to be disposed for cleaning, said housing being hinged to the table 110 so that it may be shifted away from the cleaning element.

3. A bobbin cleaning machine including a 115 table, a rotating cleaning element mounted upon the table and having card clothing on its periphery, means for rotating said element, and a guard housing partially inclosing the cleaning element and having an opening on its upper side through which the cleaning element projects. 120

In testimony whereof I hereunto affix my signature in the presence of two witnesses.

ARTHUR L. BURTON.
